UNITED STATES PATENT OFFICE.

TRUMAN MABBITT, OF VINELAND, NEW JERSEY.

BATH-TUB OR BATHING APPARATUS.

SPECIFICATION forming part of Letters Patent No. 674,704, dated May 21, 1901.

Application filed August 8, 1900. Serial No. 26,237. (No model.)

To all whom it may concern:

Be it known that I, TRUMAN MABBITT, a citizen of the United States, residing at Vineland, county of Cumberland, State of New Jersey, 5 have invented a new and useful Improvement in a Bath-Tub or Bathing Apparatus, which improvement is fully set forth in the following specification and accompanying drawings.

My invention consists of an improvement 10 in a bath-tub or bathing apparatus which may be converted into a cabinet and heated by means for producing the effect of an ordinary water or sponge bath or air, vapor, medicated, electric, Turkish, Russian, or other 15 bath, the construction of the same being hereinafter described, and the novel features pointed out in the claims that follow the specification.

Figure 1 represents a vertical section of a 20 bathing apparatus embodying my invention, the same being taken on line *xx*, Fig. 2. Fig. 2 represents a top or plan view thereof. Fig. 3 represents a section of a detached portion, on an enlarged scale, on line *yy*, Fig. 2.

Similar letters of reference indicate corresponding parts in the figures.

Referring to the drawings, A designates a bath-tub, within which is the seat B, the same being elevated above the bottom of the tub, 30 forming the chamber C for the reception of a heating medium, in the present case that of a gas burner or stove, to which, however, I do not limit myself.

D designates a flue which extends forward 35 from the chamber C and is in communication therewith and provided with a discharge-pipe or chimney E, whereby the products of combustion are directed from the chamber C into the flue D and discharged through said chimney E. The chimney E rises within the tub, so that its heat may be communicated to the fluid within the latter, whereby a small heating device, such as a gas-burner, may be used, and provision is thus made for a long heating-surface, the products of combustion escaping from said chimney through an opening E' in the wall of the tub.

It will be seen that the chamber C may be heated and the heat communicated to the 50 water in the tub. The bather may occupy the seat B and his limbs straddle the flue D and occupy the channels or spaces F along-

side of the same, and he may subject himself to baths determined upon by the change of fluids in the tub or the omission of the fluids 55 for the purpose of a hot-air bath, or by cutting off the heat take a cold-air bath, it being evident that when heat is employed the burner, stove, lamp, &c., may be regulated by the bather. It is also evident that the tub 60 may be heated from within the same by means of a vapor, electric, or other lamp, and other forms of baths may readily suggest themselves.

The bottom G is formed of wood for stiffening and strengthening purposes, and has a pipe H connected with the discharge-outlet H' in the bottom, one limb of said pipe projecting outside of the wall of the tub, where it is provided with a coupling J for 70 connection of a flexible pipe K, whereby the contents of the tub may be discharged, said pipe when the tub is in use being hung on the staple or ring L on the tub, so that it is elevated sufficiently to prevent the water or 75 fluid from escaping.

A space D' exists between the flue D and the wall of the tub below the chimney E, the same forming a passage, which intersects said flue to permit the circulation of the water or 80 fluid from side to side of the tub.

In order to inclose the top of the tub, after the order of a cabinet, I employ the frame M of skeleton or open form, the upright members of which are fitted in eyes N on the wall 85 of the tub, said eyes being provided with set-screws P, whereby the frame may be vertically adjusted. A blanket or canopy Q, of suitable fabric or material, is supported on said frame and forms a cover for the top of 90 the tub, so that the occupant may be enveloped in the heat, vapor, &c., in the tub without loss of the same. The opening E' in the wall of the tub is in the side thereof, whereby the products of combustion cannot enter said 95 canopy. The head of the occupant may protrude upwardly through the canopy or cover for breathing purposes; but if it is desired to include the head below the top of the canopy an air-pipe may be employed, the same passing 100 through the canopy to the atmosphere and reaching to the mouth of the occupant.

When the canopy is employed, the occupant may stand on the floor G or rest on the

seat B or an elevated seat supported on the top of the tub, as shown in dotted lines, Fig. 1. The discharge-opening E' of the chimney E extends laterally from the upper end of the body of said chimney and through the wall of the tub and so opens to the atmosphere below the top of the tub and below the bottom terminal of said canopy, whereby the products of combustion do not enter said canopy.

10 Various changes in the manner of using and manipulating the apparatus will suggest themselves without departing from the spirit of the improvement, it being evident that the apparatus is portable or may be made stationary and is of an inexpensive and non-complicated nature.

Having thus described my invention, what I claim as new, and desire to secure by Letters Patent, is—

20 1. The combination with a tub of a bathing apparatus substantially of the character stated, of a flue, a heating-chamber at one end of said flue, and a chimney at the other end thereof, said chimney rising within said tub and having a laterally-extending discharge-opening, a canopy on said tub, and means on the tub for sustaining said canopy, said chimney having a discharge-opening which extends laterally from the upper end 25 of the body of the chimney through the wall of the tub below the top of said tub and the bottom of said canopy.

2. The combination with a tub of a bathing apparatus substantially of the character stated, of a heating-chamber, a seat in the tub constituting the top of said chamber, a

flue extending horizontally forward from said chamber, a chimney at the discharge end of said flue, and channels on the sides of said flue extending forwardly from the inner vertical walls of said heating-chamber to the opposite end of the tub. 40

3. The combination with a tub of a bathing apparatus substantially of the character stated, of a heating-chamber, a seat in the tub constituting the top of said chamber, a flue extending horizontally forward from said chamber, a chimney at the discharge end of said flue, channels on the sides of said flue extending forwardly from the inner vertical 45 walls of said heating-chamber to the opposite end of the tub, and a transverse passage leading from channel to channel and intersecting said flue. 50

4. A tub of a bathing apparatus substantially of the character stated, in combination with a heating-chamber at one end of said tub, a seat within the tub forming the top of said chamber, a flue extending forwardly from said heating-chamber, a chimney at the 55 end of said flue opposite to said chamber, channels at the side of said flue extending from the inner vertical walls of said chamber to the opposite end of the tub, an elevated canopy supported on the tub, and a discharge-opening extending laterally from the top of said chimney through the wall of the tub below the bottom terminal of said canopy. 60
